(57) **CLAIM**

The ornamental design for a razor, as shown and described.

DESCRIPTION

FIG. 1 is a perspective view of a razor;

FIG. 2 is a front elevation view of the razor;

FIG. 3 is a rear elevation view of the razor;

FIG. 4 is a left side view of the razor;

FIG. 5 is a top plan view of the razor;

FIG. 6 is a bottom plan view of the razor; and,

FIG. 7 is another perspective view of the razor.

The broken lines illustrate a portion of the razor and form no part of the claimed design.
